ESCUTCHEON PLATE

La Verne E. Clayton, Rockford, Ill., assignor to
Amerock Corporation, Rockford, Ill., a corpora-
tion of Connecticut

Filed Feb. 23, 1968, Ser. No. 10,693

Term of patent 14 years

(Cl. D50—6)

FIGURE 1 is a front view of an escutcheon plate incorporating my new design.

FIG. 2 is a side view of the plate as seen from the right of FIG. 1.

FIG. 3 is an enlarged sectional view taken along the line 3—3 in FIG. 1.

I claim:

The ornamental design for an escutcheon plate, as shown.
